(57) **CLAIM**

The ornamental design for a machine vision target, as shown and described.

DESCRIPTION

FIG. 1 is a top perspective view of a machine vision target made in accordance with the subject design.

FIG. 2 is a bottom perspective view thereof.

FIG. 3 is a top view thereof.

FIG. 4 is a bottom view thereof.

FIG. 5 is a left side view thereof.

FIG. 6 is a right side view thereof.

FIG. 7 is a rear view thereof; and,

FIG. 8 is a front view thereof.

The claim is for the edges that are shown in solid lines. The broken lines illustrate portions of the article and form no part of the claimed design.

1 Claim, 4 Drawing Sheets
